UNITED STATES PATENT OFFICE.

JOHN L. YOAKUM, OF FOWLER, INDIANA.

TOY VEHICLE.

1,026,545.

Specification of Letters Patent.

Patented May 14, 1912.

Application filed January 20, 1912. Serial No. 672,313.

To all whom it may concern:

Be it known that I, JOHN L. YOAKUM, a citizen of the United States, residing at Fowler, in the county of Benton and State 5 of Indiana, have invented new and useful Improvements in Toy Vehicles, of which the following is a specification.

This invention relates to toy vehicles, and has for its object to provide means for imparting oscillatory or wave-like movements 10 to the body thereof as the vehicle is propelled whereby considerable amusement will be furnished the occupants.

Another object of the invention is to provide a vehicle in which the main body supporting member will be positioned in the body and at a point adjacent to the occupants' seats so that the occupants may grasp 15 the member to be held thereby against accidental falling from the vehicle as the body rocks.

In the drawing, forming a portion of this specification and in which like numerals of reference indicate similar parts in the several views:—Figure 1 is a perspective view. 25 Fig. 2 is a longitudinal section therethrough, Fig. 3 is a section on line 3—3 of Fig. 2.

The vehicle comprises a wheel base or frame which includes the side members 1, 30 the pivoted front axle 2 and the revolvably mounted rear axle 3. The front axle is provided with loosely mounted supporting wheels and the rear axle is fixedly mounted to relatively large driving wheels 5. The 35 body 6 of the vehicle may be of any suitable construction and design or configuration, being preferably provided at its opposite ends with seats 7 for the occupants.

With a view of permitting the body 6 to 40 be freely oscillated on the supporting frame of the vehicle I provide the longitudinal bars 1 with standards 8 whose upper ends are provided with bearings 9. The main supporting member for the body 6 comprises 45 a rod 10 which extends through the bushings 11 in the side walls of the body 6, the ends of said rod being mounted in the bearings 9. The ends of the rod 10 are provided with removable cotter pins or like fastening devices 50 12 that can be readily disengaged from the

rod so as to permit the latter to be disconnected from the vehicle body 6 if desired for the purpose of furnishing the body with suitable repairs. The rod 10 is disposed above the plane of the bottom of the body 6 55 and it is interposed between the seats 7. The rod is embraced by a suitable hand grip 13 which may be grasped by the hands of the occupants whereby the occupants will be guarded to an extent against accidental falling from the vehicle as the motor is propelled. 60

The rear driving axle 3 which is secured to the large wheels 5 is provided intermediate of its ends with a crank portion 14 which 65 is connected in any suitable well known manner with the body 6, preferably through the medium of the pitman rod 15 so that the motion transmitted to the axle 3 as the vehicle is propelled will be transmitted to the 70 vehicle body. In this manner it is seen that as the vehicle is propelled oscillatory or substantially wave-like movements will be imparted to the wagon body so as to furnish suitable amusement for the occupants thereof. 75 If desired, the front axle 2 may be connected with a tongue or draft-pole such as the one shown at 16 in Fig. 1 of the drawing.

The bushings are provided with squared 80 passages 17, and as shown, the member 10 is provided with correspondingly squared portions 18 which are fitted in said passages. In this manner the member 10 is fixed to the body 6 so that the latter rocks with the former. This construction is desirable so that 85 the hand gripping portions of the members will be always in the same positions relative to the occupants' seats 7. The said member 10 is preferably provided with oppositely extending branches 18', one of which being 90 disposed in convenient reach of the occupant of each seat.

I claim:

1. A toy vehicle comprising a wheeled frame, a rocking body thereon, means for 95 rocking the body when the frame is propelled, and a combined hand grip and body support for connecting the body with the frame.

2. A toy vehicle comprising a frame hav- 100

ing a wheeled driving axle, standards supported by the frame, a member mounted for rocking movements in the standards, a rocking body fixedly connected with said member, a seat located in the rocking body, the said member having a hand gripping portion extending in the direction of the seat, and means connecting the driving axle with

the rocking body so that as the axle is revolved the body will be rocked. 10

In testimony whereof I affix my signature in presence of two witnesses.

JOHN L. YOAKUM.
